UNITED STATES PATENT OFFICE.

JENS HERMAN CHRISTENSEN, OF HOLTE, DENMARK.

METHOD AND APPARATUS FOR PRODUCING COLORED PHOTOGRAPHIC PICTURES.

1,373,053.

Specification of Letters Patent. Patented Mar. 29, 1921.

Application filed August 2, 1918. Serial No. 247,981.

To all whom it may concern:

Be it known that I, JENS HERMAN CHRISTENSEN, a subject of the King of Denmark, residing at Holte, Denmark, have invented 5 new and useful Improvements in Methods and Apparatus for Producing Colored Photographic Pictures; and I do hereby declare the following to be a full, clear, and exact description of the same.

10 The invention has for its object a method of producing a colored picture through gluing together of two colored films one of which contains two of the part pictures while the other contains the third one and, 15 in carrying out the method, at least one of the said films before the exposure is mounted in a frame in which it remains during the chemical treatments and the drying, and from which it is removed only after having 20 been glued to the other film. In some cases the film may remain in its frame after the gluing together so that the latter becomes a frame for the completed picture. In such 25 case the film and frame are supplied as a unit by the factory.

The object of such frames is to prevent the films from contracting or from being displaced during the various steps of the process and to secure an automatic and complete registering of the part pictures.

By way of example two frames can be used in the following manner.

A thin collodion film is on one side coated with a film of collodio-silver-bromid and chlorid giving good contrasts and containing a yellow screen dye, (for instance so called filter-yellow) and on the other side with a green sensitive emulsion which may contain a red screen-dye. Furthermore a 40 piece of paper is provided with a red-sensitive emulsion, serving for the production of a blue part picture.

On the annexed drawing Figure 1 shows a form of a double frame in opened condition in which frame the paper can be stretched,

Fig. 2 a section through the same,

Fig. 3 a double frame in opened condition meant for accommodating the collodion film referred to above,

Fig. 4 a section through the same and

Fig. 5 a section through the two double frames laid together and provided with film and paper respectively, on a larger scale.

55 The double frame shown in Figs. 1 and 2 consists of the frame-pieces *a* and *c* con-

nected through hinges *b* and they can be kept together when closed by a clip *f* or some other suitable means. The frame-piece *a* has a protruding part or flange *e* 60 as shown and both of the frame pieces have holes *d* for registering pins.

The double frame shown in Figs. 3 and 4 consists of two flat frame pieces *g* and *h* connected through hinges *k* and they can be 65 held in the closed position by a clip *o*. The frame piece *g* has holes *m* and the frame piece *h* registering pins *n* as shown. The holes *m* are elongated in order to allow the 70 passage of the pins when the frame parts are swung together.

When the method is to be carried into effect the paper *p*, Fig. 5, is fixed between the parts of the frame shown in Figs. 1 and 2 so that it is stretched over the flange *e* and 75 has the coated side up and the edges of the paper are squeezed between the frame pieces. The collodion film *q*, Fig. 5, coated on both sides is held stretched between the frame pieces *g* and *h* with the yellow film turned 80 toward the frame piece *h*. These various operations are effected in ruby light, in some cases in a dark room. The two double frames are now laid together the pins *n* being inserted through the holes *d* so that the 85 two films get in close contact with one another as illustrated in Fig. 5. The exposure can now be effected either in a camera or through a colored picture which is laid on the film *q* in the frame piece *h*. After the 90 exposure the two frames are separated and the films are developed and treated further while supported in their frames. The pictures may by way of example be converted into pictures of silver-iodid and colored with 95 the respective dyes wanted in known manner. The frame pieces *g* and *h* in connection with the film in question form flat trays into which the solution of the dye in question is

100 poured one side being colored at a time each with its own dye. After coloring and in some cases fixation and mordication and washing out of the films they are dried always remaining in their frames and after drying the paper is provided with glue and the film 105 is applied to the same the frames being put together again as shown in Fig. 5 and the film and paper being pressed together. As means for gluing the films together glycerin or another substance which will not make 110 the two films in question soft may be used.

If it is desired to produce a transparent

colored picture the paper must be replaced by a glass or celluloid-plate which in most cases need not be mounted in a frame. In such case one single double frame only is used in which is mounted the film coated on both sides. The celluloid plate must then have holes corresponding to the registering pins on the frame.

In case an opaque white glass- or celluloid-plate is used a picture is obtained which may be seen in reflected light in the same manner as a picture on paper.

Having thus fully described my invention, I claim as new and desire to secure by Letters Patent:

1. The method of producing colored pictures which comprises mounting a pair of films separately and under tension, superposing said films with their faces contiguous, exposing said films, separating said films, treating each film separately, reassembling the films in the same superposed position without removing them from their mountings under tension, and fastening said films together while so superposed under tension.

2. The method of producing a colored picture which consists in coating one film on both sides, and another film on one side, mounting said films under tension, superposing said films with their faces contiguous, exposing said films while so superposed, separating said films, treating each film separately, reassembling the films in superposed position, and fastening said films together while so superposed and in their original mounting.

3. Apparatus for making colored pictures comprising a pair of double frames, said frames having means to cause them to register always in the same relative position when superposed and for mounting a film under tension in each frame so that when the films are superposed a face of one film will contact with a face of the other film. 40

4. Apparatus for making colored pictures comprising a pair of double frames, means for mounting a film under tension in each of said double frames, means on said double frames to cause them to always register in the same relative position when superposed, said frames being constructed to hold the films in such a position that when so superposed the faces of the films will be in close contact. 50

5. Apparatus for making colored pictures comprising a pair of double frames, means for mounting a film under tension in each of said double frames, means on said double frames to cause them to always register in the same relative position when superposed, and consisting of pins on one double frame engaging holes in the other double frame, said frames being constructed to hold the films in such a position that when so superposed the faces of the films will be in close contact. 55

In testimony whereof I have affixed my signature in presence of two witnesses.

JENS HERMAN CHRISTENSEN.
